UNITED STATES PATENT OFFICE

ESMOND E. WILEY, OF SAN FRANCISCO, CALIFORNIA, ASSIGNOR TO UNIVERSAL WINDOW COMPANY, OF OAKLAND, CALIFORNIA, A CORPORATION OF CALIFORNIA

LATCH FOR AWNING-TYPE WINDOWS

Application filed January 31, 1928. Serial No. 250,779.

This invention relates to hardware and particularly pertains to a sash latch for awning type windows.

It is the principal object of the present invention to provide a generally improved sash latch for awning type windows which may be utilized to operate the window and to latch the same in closed position.

In carrying out the invention into practice, I provide a latch mechanism which is mounted on the sash to cooperate with a strike plate on the window frame. The latch mechanism includes a pivotal latch bolt and a pivotal handle, the latter of which may be utilized both in operating the window and in maintaining the latch bolt latched to the strike plate on the frame when the window is closed.

One form which the invention may assume is exemplified in the following description and illustrated by way of example in the accompanying drawings, in which:

Fig. 1 is a view of the latch in latching position.

Fig. 2 is a view of the latch with the window partially open and with parts of the mechanism in section.

Fig. 3 is a view of the latch just released.

Fig. 4 is a fragmentary view showing a portion of the interior surface of the sash and the stool with my improved latch mechanism connected therewith and arranged in latched position.

Referring more particularly to the accompanying drawings, 10 indicates a sash of an awning type window and 11 the lower rail thereof. This sash is adapted to cooperate with a sash frame 12 including a sill 14 and a stool 15. Secured to the inner face of the lower rail 11 of the sash is a bracket 16. This bracket comprises a foot plate 17 which may be screwed or otherwise secured to the rail 11. Extending from this foot plate 17 is a channeled extension 18, the sides of which are parallel and spaced apart.

Arranged between the sides of the extension 18 is a latch bolt 19 which is pivoted on a pin 20 supported at its ends in the sides of the extension 18. Also pivotally mounted between the sides of the extension 18 is a handle

21. This handle 21 is pivoted at its inner end between the outer ends of the sides of the extension 18 on a pivot pin 22. At its outer end the handle 21 is provided with a grip portion 23. It is intended that this handle 21 be utilized both to operate the sash 10 and to maintain the latch bolt 19 in latched position relative to a strike plate 24 secured on the upper surface of the stool 15. This strike plate 24 is provided with a raised keeper lug 25 on its upper surface which cooperates with a projection 26 on the bottom of the latch bolt 19 to latch the sash 10 in closed position.

The latch bolt 19 has a second projection 27 which is adapted when engaging the lug 25 on the strike plate 24 to throw the projection 26 downwardly so that it will engage the inner side of the lug 25 on the strike plate, and thereby place the latch bolt 19 in latched position as shown in Fig. 3.

The latch bolt 19 is normally maintained in a non-latching position by a spring 28 interposed between the latch bolt and the top portion of the extension 18. The position of this spring is such that the latch bolt 19 will be normally yieldably held in a position with its projection 26 in a raised or non-engaging position. While in the present instance, I have shown a spring to accomplish this object, it is obvious that the latch bolt 19 may be so balanced about its pivotal point that this effect may be obtained without the necessity of providing a spring. That is to say, the end of the latch bolt opposite the projection 26 may be weighted so as to normally maintain the opposite end elevated.

To secure the latch bolt 19 in engagement with the keeper lug 25 on the strike plate 24, the handle 21 is provided with a cam surface 29 about its pivotal point 22. This cam surface 29 is eccentric to the pivotal point of the handle and is adapted to engage the contiguous end of the latch bolt 19 and to secure the latter in latching position as shown in Fig. 1. In Fig. 2, the handle is shown extended substantially horizontally and inwardly of the window while in Fig. 1 with the latch in latching position, the handle is swung downwardly to the vertical, so that it

does not project much beyond the end of the extension 18 of the bracket.

In operation of the device, it is constructed and assembled as illustrated in the drawings, and the latch mechanism is secured to the lower rail of the sash of an awning or swinging type window and the strike plate 24 is secured 5 on the stool of the sash frame.

When desiring to open the window, the handle is disposed as shown in Fig. 3 and pushed outwardly to open the window. This outward movement of the window will cause the projection 26 on the latch bolt 19 to ride over the lug 25 on the strike plate 24 and to place the end 30 of the latch bolt 19 into engagement with a notch 31 on the inner end 10 of the handle 21, so that the handle will offer a firm hand hold when the window is pushed outwardly.

When closing the window a pull is exerted 20 on the handle 21 to draw the window inwardly into position in its frame. As the window swings inwardly, the projection 26 on the latch bolt 19 will clear the lug 25 on the strike plate but the projection 27 will strike 25 against the lug 25 and cause the latch bolt to swing about its pivot and place the projection 26 in engagement with the inner side of the lug 25. This swinging movement of the latch bolt 19 will also disengage the end 30 30 of the latch bolt from the notch 31 on the inner end of the handle, so that the handle may be swung about its pivotal point. The handle 21 may then swing downwardly and 35 its cam surface 29 will engage the top of the end 30 of the latch bolt 19 and firmly secure the projection 26 on the latch bolt 19 in engagement with the inner side of the lug 25 on the strike plate 24. In this position the handle 21 will be disposed in an unobstructing 40 position as disclosed in Fig. 1, and will not in any way interfere with the use of inside screens or shutters on the windows.

From the foregoing it is obvious that I 45 have provided a neat appearing inexpensive window latch of simple construction and which will operate efficiently to latch a swinging type window in closed position.

While I have shown the preferred form of 50 my invention it is to be understood that various changes may be made in its construction by those skilled in the art without departing from the spirit of the invention, as defined in the appended claims.

Having thus described my invention, what I claim and desire to secure by Letters Patent is:

1. A latch for swinging windows comprising a keeper lug on the window frame, a 55 pivotal latch bolt carried by the sash, a handle operatively associated with the latch bolt and capable of use to operate the window, said handle being adapted to be operated to maintain the latch bolt in engagement with the keeper lug.

2. A latch for swinging windows comprising a keeper lug on the window frame, a bracket secured to the sash, a latch bolt pivoted to the bracket and adapted to engage the keeper lug when the window is closed, a handle pivoted to the bracket and normally extending inwardly from the sash so that it may be employed to operate the sash, said handle being adapted to be moved to a latching position at right angles to its normal position, and engaging means on the handle and the latch bolt causing the handle to maintain the latch bolt in engagement with the keeper lug when the handle is placed in latching position. 70

3. A latch for swinging windows comprising a keeper lug on the window frame, a bracket secured to the sash, a latch bolt pivoted to the bracket and adapted to engage the keeper lug when the window is closed, a handle pivoted to the bracket and normally extending inwardly from the sash so that it may be employed to operate the sash, said handle being adapted to be moved to a latching position at right angles to its normal position, a cam surface on the handle adapted to engage the latch bolt and maintain engagement with the latch bolt and keeper lug when the handle is placed in latching position. 80

4. A latch for swinging windows comprising a keeper lug secured on the window frame, a bracket secured to the sash and extending inwardly therefrom, a pivotal latch bolt carried by the bracket having latch means for engaging the keeper lug, means on the latch bolt adapted to engage the keeper lug when the window is moved to closed position to cause engagement of the latch means of the latch bolt and the keeper lug, and operative means to maintain said engagement. 90

5. A latch for swinging windows comprising a keeper lug secured on the window frame, a bracket secured to the sash and extending inwardly therefrom, a pivotal latch bolt carried by the bracket having latch means for engaging the keeper lug, means on the latch bolt adapted to engage the keeper lug when the window is moved to closed position to cause engagement of the latch means of the latch bolt and the keeper lug, a handle member pivoted to the bracket and adapted to be employed to operate the window, said handle being adapted to be operated to engage the latch bolt and maintain engagement of the latch means of the latch bolt and the keeper lug. 110

6. A latch for swinging windows comprising a keeper lug secured on the window frame, a bracket secured to the sash and extending inwardly therefrom, a pivotal latch bolt carried by the bracket having latch means for engaging the keeper lug, means on the latch bolt adapted to engage the keeper lug when the window is moved to closed position to cause engagement of the latch means of the latch bolt and the keeper lug. 120

tion to cause engagement of the latch means of the latch bolt and the keeper lug, a handle pivoted to the bracket and normally extending inwardly from the sash so that it may be employed to operate the sash, said handle being adapted to assume a latching position at right angles to its normal position, and engaging means on the handle and latch bolt causing the handle to maintain engagement of the latch means of the latch bolt and the keeper lug when the handle is placed in latching position.
